UNITED STATES PATENT OFFICE.

HENRY G. VOIGHT, OF NEW BRITAIN, CONNECTICUT, ASSIGNOR TO SARGENT & COMPANY, OF NEW HAVEN, CONNECTICUT, A CORPORATION OF CONNECTICUT.

LOCK.

1,369,505.

Specification of Letters Patent. Patented Feb. 22, 1921.

Application filed December 24, 1917. Serial No. 208,621.

To all whom it may concern:

Be it known that I, HENRY G. VOIGHT, a citizen of the United States, residing in New Britain, county of Hartford and State 5 of Connecticut, have invented certain new and useful Improvements in Locks, of which the following is a full, clear, and exact description.

This invention relates to locks, and more 10 particularly to a lock designed to lock a gear shift lever so that the lever cannot be moved by an unauthorized person after it has been locked in its neutral position.

The object of this invention is to provide 15 a locking device consisting of a pivoted latch and key-controlled means for operating the latch.

A more specific object of this invention is to provide means for locking a gear shift 20 lever of an automobile to the slotted guiding bracket with which these levers are usually provided, so that an unauthorized person cannot shift the gears of the automobile, and hence cannot operate the automobile.

To these and other ends, the invention 25 consists in the novel features and combinations of parts to be hereinafter described and claimed.

In the accompanying drawing—

30 Figure 1 is a fragmentary front elevation of a gear shift lever and its guiding bracket, having my improved device mounted upon the lever, the locking position of the pivoted latch being indicated in dotted lines;

35 Fig. 2 is a side elevation of the same, showing part of the case broken away to disclose the inclosed end of the sliding rod, and showing the pivoted latch operated by the rod in its raised position;

40 Fig. 3 is a view similar to Fig. 2, but showing the pivoted latch in locking engagement with the guiding bracket;

45 Fig. 4 is a sectional view on the line 4—4 of Fig. 2, looking in the direction of the arrows;

50 Fig. 5 is a rear end view of the pin tumbler lock, the eccentric disk upon the lock being shown in full lines in the position it assumes when the lever is locked against movement; and the position which the disk assumes when the lever is unlocked is indicated in dotted lines;

Fig. 6 is a sectional view taken between the rear end of the pin tumbler lock and the

eccentric disk, looking in the direction of 55 the disk;

Fig. 7 is a view similar to Fig. 5, the eccentric disk being removed; and

Fig. 8 is a longitudinal sectional view 60 through the pin tumbler lock.

In the drawings, 10 designates a gear shift lever adapted to shift the gears of an automobile. A slotted guiding bracket with which these levers are commonly provided is designated generally by the numeral 11. 65 The locking means which I have devised for locking the lever 10 relatively to its guiding bracket 11 consists of a latch 12 pivoted upon the lever 10 by means of a bolt or pin 13, a washer 14 preferably being provided between the outer face of the latch and the head of the bolt. The width of the latch 12 is preferably slightly less than the width of any one of the slots 11' 70 formed in the bracket 11. The position of 75 the pin 13 upon the lever 10 is such that when the latch 12, which is pivoted on this pin, is moved to substantially a horizontal position, the lower edge of the latch will clear the curved upper face of the bracket 80 11, as shown in full lines in Fig. 1; but when the latch is lowered, as indicated in dotted lines in Fig. 1, the outer end of the 85 latch will snugly fit in one of the slots 11' of the bracket 11, the arrangement being 90 such that while the latch 12 has its outer end positioned in one of the slots 11', as indicated in dotted lines in Fig. 1, the lever 10 cannot be moved to shift the gears operated by this lever. The upper face of the 95 latch 12 is preferably provided with a slotted lug 12', the object of which will be hereinafter described.

In order that the latch 12 may be locked in either of the two positions indicated in 95 Fig. 1, I provide a latch-operating rod 15, the lower end of which is preferably provided with a reduced portion that is inserted in the slot formed in the lug 12' above referred to. The reduced portion of this rod 100 is pivotally secured to the lug 12' by means of a pin 16. The upper end of the rod 15 is provided with a notch 17, the object of which will be hereinafter described.

Mounted upon the lever 10 is a lock case 105 18, which is preferably secured to the lever by means of rivets 19. The case 18 is so positioned upon the lever 10 that it receives

and incloses the upper end of the rod 15, which upper end extends through a rod-receiving opening formed in the lower face of the case 18.

5 Inside of the case 18 is mounted a pin tumbler lock 20. This lock is provided with a pair of projecting lugs 21, having drill holes 22 formed therein. The lock 20 is provided with the usual pin tumblers 24 operating therein. The lock is also provided with the usual key barrel 25, the end of which projects a short distance beyond the inner face of the pin tumbler extension 23. Upon the projecting end of the key barrel 25 is 10 eccentrically mounted a disk 26, this disk having a circular opening formed eccentrically therein for receiving the projecting end of the key barrel 25. The means for retaining the disk 26 upon the projecting end of 15 the key barrel consists of a small disk 27 which is secured to the end of the key barrel by screws or similar securing means 28. The outer face of the eccentric disk 26 has a circular groove formed therein concentric with 20 the opening formed in the disk, in which the small disk 27 is seated, as shown in Fig. 8. The operating means between the key barrel 25 and the eccentric disk 26 consists of a pin 28 rigidly mounted in the projecting 25 end of the key barrel 25 and extending laterally therefrom. This pin 28 cooperates with opposite walls 29 formed upon the inner face of the disk 26. A clearance space for the pin is provided in the disk 26 by 30 forming the arc-like groove 30 in the inner face of this disk. The walls 29 may conveniently be formed upon the disk by cutting a slot 31 across the inner face thereof. The means just described forms what is 35 known as a lazy connection between the key barrel 25 and the eccentric disk 26, the arrangement being such that the key barrel may be rotated through a complete circle, while the disk will be swung through only 40 approximately one-half of this circle. In order to limit the angle through which the disk 26 may be swung, I provide a lug 32 formed upon the lock 20, and having an end 45 projecting beyond the inner end of this lock, this projecting end being so positioned that it contacts with an edge of the disk 26 or with a wall of the slot 31 formed in this disk, 50 as shown in Figs. 5 and 6, thus limiting the angle through which this disk may be rotated.

The pin tumbler lock 20 is mounted within the case 18 and is rigidly secured thereto by rivets 33, which extend through the drill holes 22 formed in the lugs 21. The outer 60 end of the key plug 25 projects through a circular opening formed in the outer face of the casing 18, as shown in Figs. 1, 2 and 3. When the lock 20 is mounted within the case 18, the parts are so positioned that the outer 65 face of the disk 26 lies within the slot 17,

above referred to, formed in the rod 15, the arrangement being such that when the disk 26 is rotated about its eccentric mounting upon the key plug 25 by means of the key 70 34, the bolt 15 will be moved in a longitudinal direction to either raise or lower the latch 12 according to the direction in which the key barrel is rotated. By providing the lazy connection above referred to between the key plug 25 and the disk 26, it will be 75 seen that the key 34 may be removed from its lock when the disk 26 is moved to either of the two positions indicated in Fig. 5; that is, the key 34 may be removed from its lock when the latch 12 is locked in either of the 80 two positions indicated in Fig. 1.

From the above description, it will be seen that when it is desired to lock the lever 10 in its neutral position, the lever is shifted to the position shown in Fig. 4. The key 34 is 85 then inserted in its lock and the key barrel 25 is rotated to operate the bolt 15, so that the latch 12 will be moved to the position indicated in dotted lines in Fig. 1; that is, so that the latch 12 will have its outer end 90 moved into one of the slots 11' of the bracket 11. It will, therefore, be seen that while the latch 12 has its outer end in engagement with one of the slots just mentioned, the lever 10 will be locked in its neutral position and the same cannot be shifted 95 to operate the gears controlled thereby.

I have not attempted to describe the modifications of the construction which may be adopted without departing from the scope 100 of the invention.

I do not claim herein the specific driving connection between the eccentric disk and the key barrel as this structure is claimed in my Patent No. 1,293,258 granted February 105 4, 1919.

What I claim is:

1. In combination, a bracket, a lever co-operating therewith, a latch pivoted to said lever, an operating rod having one end pivoted to said latch, a guide on the lever in which the other end of said rod is slidably mounted, a cylinder lock including a key barrel and means for moving said operating rod by the rotation of said barrel including an eccentric disk secured to said key barrel, one end of said rod being provided with a notch in which said key barrel engages.

2. In a gear shift lever lock, a bracket 120 provided with a longitudinal passage and a transverse passage, a lever co-operating with said bracket and occupying an inoperative position in said transverse passage, a latch pivoted to said lever and projectable into 115 said longitudinal passage to prevent movement of said lever from inoperative position and key-controlled means for locking said latch in projected position.

3. In a gear shift lever, a bracket, a lever 130

coöperating therewith and movable longitudinally and transversely thereof, a latch pivoted to said lever and key-controlled means for projecting said pivoted latch into 5 engagement with said bracket to lock said lever against movement.

4. In a gear shift lever, a bracket having a longitudinal passage and a transverse passage, a lever movable therein and occupying 10 an inoperative position in one passage thereof, a latch pivoted to said lever and key-controlled means for projecting said latch into one of said passages to lock said lever in inoperative position in the other passage.
- 15 5. In a gear shift lever, a bracket having a longitudinal passage and a transverse passage, a lever normally occupying a neutral position in one of said passages, a latch pivotally mounted on said lever and key-controlled 20 means to project said latch into the other of said passages, comprising an operating rod having one end operatively secured to said latch, a casing secured to said lever

and having the other end of said rod slidably mounted therein, a cylinder lock mounted 25 in said casing, and means for shifting said rod by the operation of said lock including an eccentric disk operatively connecting said rod to said lock.

6. In combination with a gear shifting 30 lever having a coöperating bracket, means for locking said lever to said bracket, comprising a latch pivotally mounted upon said lever, an operating rod having one end operatively secured to said latch and having 35 a notch formed in a side thereof adjacent its other end, a lock casing upon said lever having an end of said rod slidably mounted therein, and a cylinder lock within said casing having an eccentric disk mounted in 40 said notch to shift said rod when said disk is rotated.

In witness whereof, I have hereunto set my hand on the 20th day of December, 1917.

HENRY G. VOIGHT.
